UNITED STATES PATENT OFFICE

2,434,103

ROAD MARKER

James R. Elliott, Port Huron, Mich.

Application November 9, 1944, Serial No. 562,668

2 Claims. (Cl. 94—1.5)

1

This invention relates to markers in general and more particularly to a marker for marking highways for traffic purposes and the like.

One of the prime objects of the present invention is to provide a simple road marker including a container so constructed as to form an anchor and reinforcement for the filler compound, with the top edge of the container disposed a predetermined distance below the top of the surface of the material of which the highway is constructed.

Another object is to provide a method of forming a marker receiving recess of predetermined dimensions in the highway as it is being constructed, and in which the marker can be easily and quickly installed.

A further object is to provide a road marker which is applicable to and which can be embedded or set in a plastic body of bituminous, cementitious and other forms of plastic pavement.

A still further object is to design a marker which includes a filler compound, the face of which is covered with a protective coating of highly wear-resistant material, which coating is also possessed of highly desirable light reflecting qualities.

With the above and other objects in view, the present invention consists in the combination and arrangement of parts, hereinafter more fully described, illustrated in the accompanying drawings, and more particularly pointed out in the appended claims, it being understood that changes may be made in the form, size, proportion, and minor details of construction, without departing from the spirit, or sacrificing any of the advantages of the invention.

In the drawings:

Fig. 1 is a top plan view showing my marker embedded in a pavement.

Fig. 2 is a sectional, edge elevational view taken on the line 2—2 of Fig. 1.

Fig. 3 is an enlarged, sectional edge view showing the wear-resistant coating in position.

Fig. 4 is a top plan view showing the removable ring and block used to mold the marker receiving recess in a pavement.

Fig. 5 is a sectional edge view thereof.

Fig. 6 is a plan view of the contractable ring.

Referring now more specifically to the drawings in which is shown the preferred embodiment of my invention. The pavement in which the marker is to be installed is indicated at "P," and can be formed of any cementitious, bituminous, or plastic material, this marker is of predetermined size and depth, having a preferably crowned face as shown, and when embedded in

2

position, this crowned face projects above the surface of the pavement, consequently, it is desirable that these markers be installed after the pavement has been laid and finished, otherwise the projecting face would interfere with the use of a straight edge or leveling board such as used in floating and finishing the surface of the pavement.

To provide for the installation of the marker after the pavement is finished, I mold a suitable recess 20 in the pavement as it is being constructed, providing a flat block 21, preferably but not necessarily formed of wood, and mounting a split metal ring 22 thereon so that it forms a rim for the block, said ring being resilient and is inwardly sprung so that it firmly clasps the block when assembled therein, and so that it contracts, as indicated in Fig. 6 of the drawings, when the block is removed. This block 21 can be in one piece as shown, or it can be split if desired, and can be covered with a suitable lubricant to repell moisture and facilitate the easy removal etc.

In practice, the block and ring assembly is placed in predetermined position in the pavement as it is being laid, the face of the assembly being exactly flush with the face of the pavement, thus eliminating any interference with a straight edge or other tools (not shown), utilized in the construction and finishing of the pavement.

After the pavement material has "set," the block 21 is removed, the ring 22 then automatically contracts, as indicated in Fig. 6 of the drawings, freeing itself from the material, and it can then be picked up for further use.

The marker proper comprises a cup-shaped stamping 10 which can be formed of metal, plastic, or other suitable material, said stamping having a centrally disposed opening 11 in the bottom wall 12 thereof, and a plurality of circumferentially spaced-apart, raised sections 13 are pressed in said wall. Openings 14 are provided in the raised sections 13 to permit flow of the filler compound F therethrough as the stamping is being filled, this compound when "set," being securely anchored in the stamping, and the openings 14 further serve as air vents to permit escape of air as the stamping is being filled.

To further lock and anchor the filler compound in the stamping, I enlarge the cylindrical section 50 of the stamping at the point 15, directly adjacent the bottom wall, and when the compound is poured into the stamping, it readily flows into and fills this section, thus further anchoring the filler in position. The shape of the enlarged 55 sections insures easy and thorough filling; it also

eliminates the forming of air pockets when the compound is being poured into the stamping, and the projection aids in anchoring the marker in the pavement.

In order that the marker, when installed, may be more readily observed by both drivers and pedestrians, it is formed with a convex upper face which projects above the face of the pavement, this convex face also shedding rain, dirt and snow. When desired, this convex face is covered with a plastic skin or covering 16 (see Fig 3 of the drawings), said cover being formed with an annular rib 17 which overhangs the cylindrical skirt 18 which extends into the stamping, and a plurality of circumferentially spaced openings 19 are provided in this cylindrical skirt so that as the filler compound is poured into the stamping, it freely flows into said openings, and when the compound is "set," the cover 16 will be securely held and locked in position, and this cover can also be formed with luminous beads embedded in the plastic covering, so that a luminous effect will be produced when vehicle lights are reflected thereon.

These markers are filled bottom-side up, and the nature of the outer skin or covering 16 precludes any chipping or cracking of the filler compound.

When installing the markers, the workman first places a dab of cement or other compound in the hole or recess 20, the pre-cast marker is then spotted in the recess and tapped to force it in proper depth, after which a hot sulphur compound S is poured in the surrounding space, this compound flowing in under and around the marker, and when "set," securely anchors it in position.

I wish to direct particular attention to the fact that the upper edge of the stamping that contains the filler compound is disposed a predetermined depth below the face of the pavement when it is set in position, and this is of prime importance because no metal or sharp edges which might be worn or torn to produce sharp edges, etc., is exposed, thus eliminating the possibility of injury to vehicle tires on high-speed roads, there is no reflection of light on metal, but it nevertheless serves to securely anchor the filler compound and prevents cracking or injury thereof.

While in the present instance I have shown and described a round marker, it will be under-

stood that it is for the purpose of illustration only, and that the invention includes rectangular or any other desired shape, and all other modifications and equivalents that fall within the scope of the subject matter claimed.

What I claim is:

1. A marking device of the class described comprising a rigid container formed with individual raised sections and perforations in the bottom wall thereof, a filler compound anchored in said container with its upper body portion projecting a predetermined distance above the upper edge of the container, a plastic skin forming a covering for the upper end of the container with the edges anchored in said container, and an overhanging rib formed on said covering, and disposed over the upper edge of the container.

2. A marking device of the class described comprising a rigid container formed with individual raised sections and perforations in the bottom wall thereof, a filler compound anchored in said container with its upper body portion projecting a predetermined distance above the upper edge of the container, a plastic skin forming a covering for the upper end of the container, said covering being formed with a depending skirt section extending into said container, and a plurality of openings in said skirt for admitting the filler compound to securely anchor the covering on the marker.

JAMES R. ELLIOTT.
